Primary Examiner — Mark Goodwin(74) *Attorney, Agent, or Firm* — Fish & Richardson P.C.**(57) CLAIM**

The ornamental design for side panel for a road construction machine, as shown and described.

DESCRIPTION

FIG. 1 is a right side view of a side panel for a road construction machine showing my new design.

FIG. 2 is a front view thereof.

FIG. 3 is a left side view thereof.

FIG. 4 is a rear view thereof.

FIG. 5 is a top plan view thereof.

FIG. 6 is a bottom plan view thereof.

FIG. 7 is a top, front, right side perspective view thereof; and,

FIG. 8 is a further top, rear, right side perspective view thereof.

1 Claim, 8 Drawing Sheets(56)
